UNITED STATES PATENT OFFICE.

EDWIN T. LIGON, OF DEMOPOLIS, ALABAMA.

PUMP.

SPECIFICATION forming part of Letters Patent No. 224,193, dated February 3, 1880.

Application filed April 8, 1879.

To all whom it may concern:

Be it known that I, EDWIN T. LIGON, of Demopolis, in the county of Marengo and State of Alabama, have invented a new and useful Improvement in Pumps, of which the following is a specification.

Figure 1 is a detail section of a portion of a pump cylinder and piston illustrating my invention. Fig. 2 is a cross-section of the cylinder. Figs. 3 and 4 are detail views of the piston, showing modifications of construction.

Similar letters of reference indicate corresponding parts.

15 The object of this invention is to furnish improved pumps which shall be simple in construction, inexpensive in manufacture, strong, and durable, and which at the same time shall be self-packing.

20 The invention consists in pump cylinders and pistons formed of spirally-wound wires or strips firmly soldered together, in pump-cylinders formed of spirally-wound wires or strips firmly soldered together and having metal 25 cast around their outer surfaces, and in pump-pistons formed of spirally-wound strips or wires firmly soldered together and having strips or wires, or strips and wires, wound spirally around their outer surfaces, as herein- 30 after fully described.

The cylinder is made by taking a rod of the requisite diameter, and which is made perfectly true, such as is made by the cold-rolled process, and winding around it spirally a wire 35 or strip, A, of brass, or of steel or iron coated with tin or zinc, and soldering it together, while in place, either by immersing it in melted metal or in any other suitable and convenient manner.

40 If additional strength is required, the wire tube is placed in a mold somewhat larger than the said wire tube, and the intermediate space is filled with melted metal B.

This construction may also be applied with 45 advantage to the construction of the cylinders of small engines, as it would dispense with much of the present costly lathe-work, and by using steel wire or strips the cylinders would be much more durable than when made in the 50 usual way.

The body of the piston may be formed of

coiled wire or strips A, soldered together, or it may be cast, and has strips or wires C, or strips and wires C, wound spirally around it.

Fig. 1 shows a piston with strips C wound spirally around it. Fig. 4 shows a piston with wire C wound spirally around it; and Fig. 3 shows a piston with strips and wire C wound spirally around it, the wire being of a greater diameter than the thickness of the strips, and being placed between the adjacent edges of the said strips.

With this construction the spiral spaces between the wires or strips detain the water sufficiently to cause it to serve as a packing, 65 thus making the pistons self-packing and rendering the use of leather or other packing unnecessary.

In case a cast piston-body be used, the spiral strips or wires should be turned true in 70 a lathe, the surface of the said cast body, between the said spiral strips or wires, being left rough, to still further retard the descent of the water packing.

The valve is designed to be placed at the 75 top of the piston, which position gives more room for the passage of the water.

This construction allows the tubing and piston to be made square or of other polygonal shape, and in that case, in very deep 80 wells, the bucket or piston can be attached, by means of a small wire cable, to a wheel above, and by working the wheel backward and forward the tube may be filled with water, which may then all be raised by winding up the said 85 cable. In this case the shape of the tube and piston will keep the cable intact and prevent its unwinding.

A small valve may be inserted in the side of the tube some twenty or thirty feet above the 90 surface of the water, to admit air under the bucket or piston when it has passed that point, to relieve it of atmospheric pressure, and thus lessen the subsequent labor.

Having thus described my invention, I 95 claim as new and desire to secure by Letters Patent—

1. Pump cylinders and pistons formed of spirally-wound wires or strips A, firmly soldered together, substantially as herein shown 100 and described.

2. Pump-cylinders formed of spirally-wound

wires or strips A, firmly soldered together, and having metal B cast around their outer surfaces, substantially as herein shown and described.

5 3. Pump-pistons formed of spirally-wound strips or wires A, firmly soldered together, and having strips or wires, or strips and wires,

C wound spirally around their outer surfaces, substantially as herein shown and described.

EDWIN T. LIGON.
